[57] CLAIM

The ornamental design for a lantern, as shown and described.

DESCRIPTION

FIG. 1 is a front, left side perspective view of a lantern showing our new design;
FIG. 2 is a top plan view thereof on an enlarged scale;
FIG. 3 is a left side elevational view thereof on an enlarged scale, the right side being a mirror image;
FIG. 4 is a front elevational view thereof on an enlarged scale;
FIG. 5 is a rear elevational view thereof on an enlarged scale;
FIG. 6 is a bottom plan view thereof on an enlarged scale; and,
FIG. 7 is a front, left side perspective view of the lantern pivoted on its base to an alternate position.
